UNITED STATES PATENT OFFICE.

JOHN VAN VLECK, OF NEW YORK, N. Y., ASSIGNOR TO CHRISTOPHER D. SMITHERS, OF SAME PLACE.

ELECTRIC GLOW-LAMP.

SPECIFICATION forming part of Letters Patent No. 644,783, dated March 6, 1900.

Application filed May 9, 1899. Serial No. 716,134. (No model.)

To all whom it may concern:

Be it known that I, JOHN VAN VLECK, of the city, county, and State of New York, have invented a new and useful Improvement in Electric Glow-Lamps, of which the following is a specification.

My invention relates to that class of electric glow-lamps in which the light is emitted from a body of refractory material which at normal temperatures is a non-conductor, but which upon being heated to a certain point becomes a conductor, and is thus rendered incandescent by the passage of the current.

The mode of organization of my invention consists in combining with such a non-conducting body a device for heating the same by means of a flame produced in proximity to said body and means for controlling the supply to said flame and for igniting the same, the said means being constructed and arranged so that when the said body is rendered conducting said supply shall be cut off and circuit broken through the igniter.

My invention further consists in the electromagnetic devices for accomplishing the foregoing and their combinations and also the various other novel features embodied, all as hereinafter more particularly pointed out in the claims.

In the accompanying drawings, Figure 1 is a side elevation of my lamp. Fig. 2 is a vertical section with the inclosing case omitted, and Fig. 3 is an electrical diagram showing the circuits in the lamp.

Similar letters and numbers of reference indicate like parts.

The term "glower," hereinafter used for brevity, means a body of non-conducting material which is raised in temperature by the heater, and thus becomes a conductor and permits the passage of the electrical current, which causes it to glow.

The term "heater," hereinafter used, means a device whereby the glower, normally non-conducting, is elevated in temperature, so as to become a conductor of the electrical current.

The general arrangement of my lamp will be best understood by first referring to the electrical diagram, Fig. 3. *a* is a glower, here shown in the form of a curved rod of suitable

refractory material, which may be, for example, magnesia. The heater is indicated at *b* and, as will hereinafter be described in detail, is embodied herein in a gas-burner, which emits a flame, which flame impinges upon the glower *a*, and thus raises said glower in temperature. This heater is so constructed that the current separates terminals at the apex of the burner to produce an igniting-spark and also actuates the valve which admits gas to the burner to be ignited by that spark. The terminals to be separated are indicated at *p* in Fig. 3, and the electromagnet which controls them and the valve is at *d*. At *f* is a spark-coil or any other means of introducing suitable resistance to aid in the production of the spark at the terminals *c*. At *g* is a pivoted lever adapted to make and break circuit at *h*. This lever carries the armature *i* of the electromagnet *d* and is controlled by that magnet.

Still referring to Fig. 3, the lead of the circuits is as follows: The wire *e* is connected to any suitable source of electricity, and thence circuit proceeds through the contact-points at *h* by way of the conductor *j* to the coil of the electromagnet *d*, and thence by wire *k* to ground. A branch connects with wire *j* at *l*, includes the spark-coil *f* and igniting-contacts at *p*, and meets the ground-wire *m* at *n*. The main circuit through *e* proceeds through the electromagnet-coil *c*, through the glower *a*, and connects with the ground-wire *m* at *o*. The wire *m* instead of being grounded may be a return to the source of electricity. The operation is then as follows: The current established at *e* proceeds through the contacts at *h*, which are normally together, thence through wire *j* and coil *k* to ground, thus energizing electromagnet *d* and causing it to attract its armature. Part of the current proceeds from *l* through the spark-coil *f* and contacts *p* to ground. When electromagnet *d* attracts its armature, as aforesaid, the contact-points *p* are separated and the gas-valve is opened. The separation of contacts *p* produces a spark which ignites the escaping gas and the flame, rising, meets the glower and heats it. As soon as glower *a* is brought to the proper degree of temperature current may pass from wire *e* through the coil *c* and through

the glower to wire *m* and so to ground. Electromagnet *c* then becomes energized, attracting its armature *i* and so breaking circuit at *h* and causing the electromagnet *d* to release its armature, which by the action of the spring closes the gas-valve and so shuts off the flame, thus throwing the heater out of operation. The glower *a* thus being rendered incandescent by the current continuously passing through it emits the required light.

Referring now to Fig. 2, which shows a construction embodying my invention, 1 is a socket internally threaded and adapted to be attached to the gas-pipe. From this socket 15 extend downwardly two tubes 2 and 3. These tubes at their lower ends communicate with a separate tubular casting 4. The gasway 5 in said casting is surmounted by a Bunsen burner 6, the air-apertures of which are shown 20 at 7. Between this burner and the casting 4 is secured the valve-seat 8. 9 is a gas-valve conical at its upper portion and entering said seat. The seat is tubular to receive a rod 10, secured to the gas-valve and preferably made 25 spiral in form at its end, as shown. The end of this rod extends a little above the top of the burner 6 and forms one electrode of the circuit-breaker *p*. The other electrode 11 is secured in a collar 12 on the exterior of the burner 6 and is insulated therefrom, as shown. The electrode 11 is bent over, so as normally 30 to rest upon the tip of the rod-electrode 10. The electrode 11 is fixed in the collar 12. Secured beneath the casting 4 is an internally-threaded bracket 13. This bracket is threaded 35 on its inner periphery to receive the cup-shaped piece 14, which has an inner tube 15, through which tube the rod 9 extends and terminates below in a ring 16. The electromagnet-coil *d* is placed in this cup-shaped piece 40 and surrounds the inner tube 15 thereof. Within the cup-shaped piece 14 and above the magnet-coil *d* is placed the armature 17. This armature has a central sleeve 18, of insulating material, through which sleeve the valve 9 passes. The inner periphery of the cup-shaped piece 14 is flanged to receive the threaded flanged cover 19. The sleeve 18 is flanged at its upper portion, and between the 45 flange and the cover 19 is interposed a spiral spring 20.

The tube 3 is preferably made in two parts to receive a union 21. Between the union 21 and the sleeve 22 on the tube 3 and preferably integral with said union and sleeve is a supporting-platform 23. The platform is secured by a suitable screw to the upright 24, to the upper end of which is pivoted the lever *g*, which carries the armature *i*. This armature is disposed above the core 25 of the electromagnet-coil *c*. The coil and core are secured to the platform 23 by a screw 26. Also rising from the platform 23 is an upright 27, which carries the fixed or upper electrode 28 of the pair of contacts marked *h* in Fig. 3. The lower electrode 29 of this pair of contacts is secured to the armature-lever *g*.

The electrodes 28 and 29 are threaded and pass through correspondingly-threaded sleeves 30 and 31, of insulating material, inserted, respectively, in the upright 27 and lever *g*. The object of threading the electrodes is to enable them to be adjusted with reference one to the other. The upright 27 extends upward beyond the electrodes, as shown at 32, and forms an arm, to which is secured the retracting-spring 33, which connects with the armature-lever *g*. The spark-coil *f* is indicated diagrammatically in Fig. 2. On the lower side of the platform 23 is secured in any suitable way a support 34, of insulating material, through which extend wires 35, between which and beneath the support extends the glower *a*.

I will now trace the circuit with reference 85 to the parts detailed. The wire *e*, being connected to any suitable source of electricity, proceeds down through the tube 3 to the union 21 and thence to the upper electrode 28 of the pair *h*, thence to the lower electrode 29 90 when said electrodes are in contact, and thence by wire *j*, which is in the lower part of the tube 3, through a vertical opening 36 in the casting 4 and the side openings in the bracket 13 and cup 15 to the coil *d*, and through that 95 coil to the return-wire *m*, or instead of going to a return-wire *m* the circuit may end with the cup 15, in which case the current will proceed through the tube 2 to the wire 37, which is connected thereto. The branch circuit from 100 *l* proceeds through the spark-coil *f* and thence by the wire 38 to the connecting-screw 39, by which that wire is secured to the upper electrode 11 of the igniting pair *p*. This wire in passing through the casting 4 traverses an 105 insulating-sleeve 40. The circuit also proceeds from the wire *e* by way of the wire 41 to the electromagnet *c*, and thence to the glower *a*, and thence to the screw 42, to the upright 27, and so to the metal part of the 110 fixture, and thus to wire 37; or, if desired, a separate connection from 42 may be carried directly to the return-wire *m*, the circuit in either case being completed.

The operation with reference to this construction is then as follows: The spring 33 actuates the armature *i*, so that the electrodes 28 and 29 at *h* are in contact. A part of the current thus passes from wire *e* through these electrodes 28 and 29 by wire *j* to the electromagnet *d* and so to ground or wire *m*, while another part of it proceeds through the spark-coil *f* by way of wire 38 to the upper electrode 11 of the igniting pair *p*, thus to the lower electrode 10, and then to the valve 9 120 and so to the metal part of the apparatus, and then by wire 37 to ground. Circuit is therefore established simultaneously between the sparking-electrodes 10 and 11 and also through the magnet *d*. The spark-electrodes are normally held in contact by the action of the spring 20 bearing against the flange 18 and the cover 19, the effect being to raise the armature 17 and the valve 9, which it incloses,

so that by the action of this spring not only are the electrodes 10 and 11 held in contact, but the valve is held close to its seat 8. Now when current is established between the igniting-electrodes and through the electromagnet *d*, as described, the electromagnet *d* draws down its armature 17, this pulling upon the valve 9 against the action of the spring 20. Gas is therefore free to pass through the tube 2 to the Bunsen burner and to emerge from the tip thereof; but at the same time the electrode 10 is drawn away from the electrode 11, thus breaking circuit at this point and producing a spark between said electrodes, which 15 spark ignites the escaping gas-current. The flame then rises upward and meets the glower *a* and heats the same up to the point where that glower *a* becomes a conductor. As soon as this state of affairs is established the current from wire *e* may proceed by wire 41 to the electromagnet *c*, through the glower to pin 42, and so through the metal part of the apparatus to wire 37. The electromagnet *c* then 20 attracts its armature *i*, pulling down the pivoted lever *g* and separating the electrodes 28 and 29, and that breaks the circuit through the igniting-electrodes and through the electromagnet *d*. The spring 20 therefore is free to draw the armature 17 back to its original 25 position, thus closing the valve 9 to its seat and shutting off the gas-supply and putting out the gas-flame and once more bringing the igniting-electrodes 10 and 11 into contact. The only remaining circuit, therefore, which 30 is closed in the apparatus proceeds through the glower *a*, which is thus continuously rendered incandescent and brightly glows.

The platform 23 carries on its upper side a dome-shaped cover 43, which is readily removable and which serves to protect the working parts beneath it. On the under side it carries a convex reflector 44, through an opening in which the support 34 of the glower *a* protrudes. In Fig. 1 I show sheet-metal casings, one of which at 45 covers the lower part of the apparatus beneath the heater and is secured in place by any suitable means. The other, 46, covers the upper portion of the apparatus. Between these two casings and surrounding the tubes 2 and 3 is interposed a tubular envelop 47, of glass, which is held between the casings 45 and 46. In the lower casing 45 I make ventilating-openings 48, and in the upper casing 46 similar ventilating-openings 49, so that an air-current may pass in at 48, rise through the envelop 47, and escape by the openings 49.

It will be noticed that the valve 9 may be drawn downward by means of the ring 16 on its lower end by hand. It may be operated in this way to open the valve and separate the spark-electrodes when desired. This guards against any possible failure of the heater to be operated by the current, since it will be noticed that the circuit from the controlling-electromagnet *c* goes to screw 42 on

the upright 27, and thus communicates directly with the ground. Hence if the mechanism controlling the heater should for any cause be injured the valve 9 can be worked 70 by hand to produce the desired flame. As soon as the glower is heated the operation of the lamp will go on as usual. Of course any kind of combustible gas may be used to supply the Bunsen burner. 75

I claim—

1. In an electric lamp, a glower, means for producing a flame to heat the same and means for extinguishing said flame controlled by the current established in said glower, substantially as described. 80

2. In an electric lamp, a glower, means for producing a flame to heat the same and means for controlling the supply of combustible to said flame controlled by the current established in said glower, substantially as described. 85

3. In an electric lamp, a glower, means for producing a gas-flame to heat the same, and means for cutting off the gas-supply to said flame controlled by the current established in said glower, substantially as described. 90

4. In an electric lamp, a glower, a source of gas-supply, a burner communicating with said source and producing a flame adapted to heat said glower and means for controlling the gas-supply to said burner through the current in said glower, substantially as described. 95

5. In an electric lamp, a glower, means for producing a flame adapted to heat said glower and means for igniting said flame controlled by the current in said glower, substantially as described. 100

6. In an electric lamp, a glower, a source of gas-supply, a burner communicating with said source and producing a flame adapted to heat said glower, a valve controlling the gas-supply to said burner and an igniter for said burner; the said valve and the said igniter being controlled by the current in said glower, substantially as described. 105

7. In an electric lamp, a glower, means for producing a flame to heat the same, an electromagnetic device for controlling the ignition of said flame, and the supply of combustible thereto, and means for controlling said electromagnetic device actuated by the current established in said glower, substantially as described. 115

8. In an electric lamp, a glower, an electromagnet in circuit therewith, a circuit-breaker controlled by said electromagnet, means for establishing and cutting off the heat-supply to said heater, an electromagnet controlling said means and circuit connections; whereby when said last-named electromagnet shall be energized it shall operate said means to establish the heat-supply to said heater, and thereafter when said glower shall by said heater have been rendered electrically conducting, said first-named magnet shall operate said circuit-breaker to cut out said last- 120
125
130

named electromagnet and cause said means to cut off the heat-supply, substantially as described.

9. In an electric lamp, a glower, a burner 5 communicating with a source of combustible, and adapted when ignited to produce a heating-flame in proximity to said glower, separable electrodes disposed at the outlet of said burner, means for cutting said electrodes 10 out of circuit, means for separating and bringing together said electrodes and circuit connections; whereby when the actuating-current is established, said means for separating said electrodes shall operate to draw them 15 apart and produce an igniting-spark at the burner and thereafter when the flame shall have rendered said glower electrically conducting said means shall operate to bring said electrodes into contact, substantially as de- 20 scribed.

10. In an electric lamp, a glower, a gas- 25 burner communicating with a source of gas-supply, a valve for said burner, an electromagnetic device controlling said valve, a circuit-breaker in circuit with said electromag- 30 netic device, an electromagnetic device in circuit with said glower and controlling said circuit-breaker and circuit connections; whereby when said valve-controlling electro- 35 magnetic device is energized it shall open said valve to admit gas to said burner to produce a heating-flame for said glower, and thereafter when said glower shall have been rendered electrically conducting said last- 40 named electromagnetic device shall operate said circuit-breaker to deenergize said valve-controlling device and thereby control said valve to shut off the gas-supply, substantially as described.

40 11. In an electric lamp, a glower, a gas- 45 burner communicating with a source of gas-supply, a valve for said burner, an electric igniter for said burner controlled by said valve, a circuit-breaker in circuit with said electromagnetic device, an electromagnetic device in circuit with said glower and controlling said circuit-breaker and circuit connec- 50 tions; whereby when said valve-controlling electromagnetic device is energized it shall open said valve to admit gas to said burner, and said valve shall actuate said igniting device to ignite said gas to produce a heating-

5 flame for said glower, and thereafter when said glower shall have been rendered electrically conducting said last-named electromagnetic device shall operate said circuit-breaker to deenergize said valve-controlling device and thereby control said valve to cut off the gas-supply, substantially as described.

6 12. In an electric lamp, having a burner 6 communicating with a source of gas-supply, the combination of the glower *a*, and electromagnet *c* in circuit, a valve controlling the supply of gas to said burner, an electromagnet *d* controlling said valve and in shunt-circuit 6 with said glower and a circuit-breaker *h* in said shunt controlled by said electromagnet *c*, substantially as described.

7 13. In an electric lamp having a burner 7 communicating with a source of gas-supply, the combination of the glower *a* and electromagnet *c* in circuit, an electric igniter dis- 7 posed at the burner-outlet, an electromagnet *d* controlling said igniter in shunt-circuit with said glower, and a circuit-breaker *h* in said shunt controlled by said electromagnet *c*, substantially as described.

8 14. In an electric lamp having a burner 8 communicating with a source of gas-supply the combination of the glower *a*, electromagnet *c*, a valve *g* controlling the supply of gas to said burner, a fixed electrode *11* at the burner-outlet a movable electrode *10* carried by said valve, an electromagnet *d* controlling said valve, a circuit-breaker *h* controlled by 8 electromagnet *c* and circuit connections, substantially as described.

9 15. In an electric lamp having a glower, a burner communicating with a source of gas-supply and adapted to produce a heating-flame for said glower, a valve in said burner and means for electrically actuating said valve and thereby establishing a supply of gas to the heating-flame, and means controlled by said glower for throwing the electrical actuating mechanism of said valve out of operation after said glower by said flame shall have been rendered electrically conducting, substantially as described.
